UNITED STATES PATENT OFFICE.

ALEXANDER P. SYGER, OF DETROIT, MICHIGAN.

INTERNAL-COMBUSTION ENGINE.

1,255,664.

Specification of Letters Patent.

Patented Feb. 5, 1918.

Application filed December 15, 1916. Serial No. 137,092.

To all whom it may concern:

Be it known that I, ALEXANDER P. SYGER, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

This invention relates to rotary internal combustion engines. It comprises a battery of cylinders having a pair of pistons in each cylinder which approach each other together and withdraw from each other at the same time. The members of adjoining pairs of pistons are connected up to move together, as will more fully appear hereinafter.

In the drawings,—

Figure 1 is a longitudinal section.

Fig. 2 is a plan view partly broken away.

Fig. 3 is a cross section on the line C—C of Fig. 1.

Fig. 4 is a cross section on the line D—D of Fig. 1.

Fig. 5 is a cross section on the line E—E of Fig. 1.

Fig. 6 is an end elevation looking at the structure shown in Fig. 1 from the left. *a* designates a cylindrical housing in which is journaled the rotor *b* in the form of a cylinder here shown as having two longitudinal bores or cylinders *c* for the reciprocating pistons *d*. The pistons in each bore move in together and move out together. The outer ends of the pistons are provided with sockets containing ball bearings, *e* which contact the cams *f*. Obviously when the reciprocating force of the pistons is brought against the inclined faces of the cams *f*, a portion of the rectilinear force is converted into a rotary motion of the rotor *b*.

The rotor *b* is keyed to the shaft *g*, whose ends are journaled in the ends of the housing *a*. On the left hand end of this shaft is a beveled pinion *h* meshing with a beveled gear *i*. On the shaft of the beveled gear *i* are two cams *j* engaging with the terminals of the rock arms *l* which connect with the rock shafts *m* that in turn are fast to the rock levers *n*. These rock levers *n* engage the ends of the valve stems *o* and serve to

push the valves off from their seats as against the force of the springs *p*.

It will be noted that the housing *a* or the casting that forms this housing is cored out at *q* to form a water-jacket to cool the parts adjacent the combustion chambers. It will also be noted that the rotor is provided with two semi-annular grooves *r* at its mid portion, and that each semi-annular groove connects through the port *s* with the combustion chamber. At opposite sides of the housing are ports *t*, the intake and the exhaust ports respectively, and these connect with suitable piping leading from the carburetor (not shown) and to the muffler (not shown). Only one spark plug *u* is required, and this can be set in a port at the top of the engine which will connect with the semi-annular grooves *r* and of course the flame will spread around the semi-annular grooves and into the port of the combustion chamber about to be fired.

The operation of the engine may be quite easily understood from Fig. 3, as it will be seen that the bottom semi-annular groove *r* connects the intake port *t* with the lower combustion chamber. It also connects with the exhaust port but the exhaust port valve is timed to be closed at this time. The engine is now upon the suction stroke. When the right hand end of the semi-annular groove *r* has passed the inlet port, the fuel charge enters upon the compression stage. The semi-annular groove *r* continues around until it reaches a point adjacent the spark plug *u*, whereupon a spark is passed between the points of the plug by a suitable timer sending the current through the plug at that time. As the rotor continues around the forward end of the semi-annular groove passes the exhaust port and the exhaust valve is opened by the valve mechanism and the burned gases allowed to escape. Of course the cycle of operations is repeated and it will be seen that one cylinder fires every two revolutions of the rotor and that the rotor has a power stroke every revolution.

The valve timing mechanism is the cams *j* which operate a valve every revolution of the rotor and either one of the valves every second revolution of the rotor.

It will be noticed that the pistons are connected up in pairs, one of the pair from one bore and the other of the pair from the other bore at the opposite end. This is accom-

plished by the guide rods z , running longitudinally through the battery of cylinders and the arms y . This is necessary so as to make them follow the cam face without the necessity of springs, as for instance, when the pistons in one bore are on the suction stroke, the pistons in the other bore are on the exhausting stroke. Hence the resistance offered to the pistons in the effort to expel the burned gases serves to keep the pistons of the other bore against the cam face and drawn out. Likewise if the pistons of one bore are on the compression stroke the pistons of the other bore are on the working stroke.

From the above description it will be seen that I have devised a rotary internal combustion engine of simple construction, in which one piston aids the other in its action. The engine is so designed that it is very compact and will occupy considerably less space than the ordinary reciprocating internal combustion engine with the connecting rod and crank shaft. Only one spark plug is required, and the engine may be quite conveniently and easily disassembled to clean out any accumulations of carbon or change the rings.

What I claim is:

30. 1. In an internal combustion engine, the combination of a battery of cylinders, cam means, each cylinder being provided with two pistons which exert force against the cam means to rotate the battery, and means 35 for connecting up the piston of one cylinder with the piston at the other end of an adjacent cylinder.

2. In an internal combustion engine, the combination of a battery of cylinders, reciprocating pistons, two in each cylinder arranged to rotate the battery when the pistons reciprocate, guide rods guided in the battery of cylinders, and a member at each end of each guide rod for connecting the 45 guide rod to a piston of an adjacent cylinder.

3. In an internal combustion engine, the combination of a housing, a rotor rotatably held therein and provided with a pair of semi-annular grooves, each having ports connecting with bores in the rotor, pistons engaging in said bores, and valve chambers 50 and valves connecting through ports with the semi-annular grooves at prescribed times

to govern the strokes of the pistons in connection with the action of the valves.

4. In an internal combustion engine, the combination of a housing, a rotor provided with a pair of longitudinal bores rotatably held in said housing, the said housing being provided with an intake port and an exhaust port, the said rotor being provided with a pair of semi-annular grooves, each being provided with a port entering the bores, a pair of pistons in each bore, and intake and exhaust valves with properly timed operating mechanism connecting with the exhaust and inlet ports.

5. In an internal combustion engine, the combination of a housing, a rotor rotatably mounted therein and provided with a plurality of cylinder bores and a pair of semi-annular grooves each having ports connected with a bore in the rotor, a pair of pistons in each cylinder bore, the pistons of each bore being arranged to move outwardly and inwardly together, means for connecting up the pistons in pairs, one from one bore and another from the other bore at the opposite end, the said housing being provided with exhaust and intake ports which connect with the semi-annular grooves at appointed times, exhaust and inlet valves having suitable mechanism for operating them at the proper times in connection with the semi-annular grooves to afford the proper working strokes 85 for the piston, and a stationary cam at each end of the rotor with which the ends of the pistons engage to cause the rotation of the rotor upon the reciprocation of the pistons.

6. In an internal combustion engine, the combination of a housing, a rotor rotatably held therein and provided with a plurality of bores forming engine cylinders and having part-annular grooves, each of which connects with an engine cylinder, pistons engaging in said bores, the said housing being provided with exhaust and intake ports opening into the space in which the rotor is located, and valves and valve chambers connecting through the ports and the part-annular grooves with the engine cylinders, substantially as described.

In testimony whereof, I sign this specification.

ALEXANDER P. SYGER.
